UNITED STATES PATENT OFFICE.

CHARLES G. NELSON, OF CHICAGO HEIGHTS, ILLINOIS, ASSIGNOR TO ZOURI DRAWN METALS COMPANY, OF CHICAGO HEIGHTS, ILLINOIS, A CORPORATION OF ILLINOIS.

SUPPORT FOR WINDOW PANES.

Application filed February 11, 1926. Serial No. 87,706.

My invention relates to a metal window sash and more particularly to an outer clamping plate and means for connecting it to an inner clamping member.

5 The object of my invention is to provide a construction whereby the outer clamping member of a metal window sash may be accurately positioned and held in such a manner that it may exert yielding pressure on

10 the glass.

The construction and the minor objects of my invention will appear as the description proceeds.

In the accompanying drawing forming a 15 part of this specification, Fig. 1 is a cross-section of a sash embodying one form of my invention; Fig. 2 is fragmentary front elevation of the same, and Fig. 3 is a view similar to a portion of Fig. 1, but showing a different form of face plate.

The sash is shown as applied to a lower frame member or sill 10 which has a horizontal portion 11 beneath the glass sheet 9, and a riser 12 behind the lower edge of the glass.

25 This sill is shown with a sheet metal cover 13 having an upturned flange 14 at its rear edge adjacent riser 12. An inner glass engaging member 15 has a substantially horizontal portion 16 the front edge of which is turned

30 down to form a flange or lip 17 adapted to contact the rear face of the sheet of glass.

At the rear edge of horizontal portion 16 there is a downwardly directed portion 18 adapted to rest against riser 12 and having

35 an offset portion 19 at its lower edge adapted to extend downward in front of flange 14 into contact with sill covering 13. Preferably offset portion 19 terminates in a forwardly directed portion 20 adapted to lie on

40 top of covering 13.

The outer clamping member or face plate 21 has a glass-engaging flange 22 at its upper edge, and has a bead 23 at its lower edge adapted to rest on sill covering 13 and to 45 abut against the forward edge of portion 20 of rear plate 15. A substantially horizontal flange 24 extends from bead 23 and is raised enough to overlie portion 20 with a slight normal clearance.

50 A sheet metal box-shaped bracket 25 lies on one side 26, which rests on portion 20, and has its bottom perforated to receive a screw 27 by which it and clamping plate 15 are held in place against riser 12. The upper side 28 of the bracket is provided with a

screw-threaded bushing 29. The front side of the bracket is open.

A substantially L shaped member 30 has the upper end 31 of its upright arm resting against flange 22, while its horizontal arm 32 60 extends rearward into bracket 25. The angle 33 of member 30 rests upon flange 24, and a portion 34 of flange 24 may be bent upward through a hole 35 in arm 32.

Arm 32 is slanted upward at 36 and then 65 has its rear end turned down at 37 to rest upon side 26 of bracket 25 and support the rear end of portion 36. Flanges 38 are preferably provided at the sides of member 30 to stiffen the member and maintain its two arms 70 at a substantially constant angle.

A screw 39 is passed downward through bushing 29 and has a rounded lower end 40 adapted to press against slanting portion 36 of arm 32 and press the arm downward and 75 at the same time draw it to the rear by means of cam action against the slanting surface.

The forward edge 41 of bracket bottom 26 is turned upward slightly, so as to furnish a 80 yielding support for arm 32, and flange 24 affords a yielding support for the angle of member 30.

Bead 23 rests upon the unyielding surface of sill covering 13, and is held against rearward movement by portion 20 of back plate 85 15, while the construction of offset portion 19 is such that bead 23 may force portion 20 slightly to the rear, this movement will not be enough to materially change the angle of the front plate.

90 It will be readily understood from the above description that, when the parts are assembled in the manner disclosed, downward movement of screw 29 results in cam action against portion 36 and draws member 30 to the rear and thereby brings the front plate against the glass and against the front edge of portion 20. Member 30 presses downward on flange 24, and this insures against bead 23 slipping over the edge of portion 20. The slight yielding allowed by portions 19, 41 and 24 is sufficient to relieve undue strain on the glass, and at the same time the front clamping plate is not allowed to move to an objectionable extent. The comparative rigidity of member 30 aids in preventing undue movement of the front clamping plate and in confining any yielding to the places mentioned above.

100 In Fig. 3 an outer clamping member or 110

face plate 21^a is shown having upper and lower flanges like those shown in Fig. 1, but having the intermediate portions extending along different lines. Parts shown in Fig. 5 are designated by the same reference numerals as corresponding parts in Fig. 1, with the letter "a" added. It will be noted that flange 24^a is slightly widened, and that the upright arm of member 30^a is modified to fit within the modified face plate. These changes are without material effect upon the operation of the device.

While I prefer to use the portion 20, it might be omitted in some cases, and various other obvious changes may be made within the scope of the appended claims, which define my invention.

What I claim is:

1. In a support for a window pane, a supporting member beyond one edge of the pane and approximately perpendicular to the plane of the pane, a clamping member having one edge adapted to rest against the pane, having its other edge adapted to rest against said support and having a flange along the second said edge extending towards the plane of the pane and spaced slightly away from the supporting member, and means to press the flange towards the supporting member.

2. In a support for a window pane, a supporting member beyond one edge of the pane and approximately perpendicular to the plane of the pane, a clamping member having one edge adapted to rest against the pane, having its other edge adapted to rest against said support and having a flange along the second said edge extending towards the plane of the pane and spaced slightly away from the supporting member, and means adapted to draw the flange towards the plane of the sheet and at the same time to press it towards the supporting member.

3. In a support for a window pane, a supporting member beyond one edge of the pane and approximately perpendicular to the plane of the pane, a clamping member having a flange along one edge adapted to bear against the pane, having its other edge adapted to bear against said support and having a flange along the second said edge extending towards the plane of the pane and spaced slightly away from said supporting member, a substantially L-shaped member having the end of one arm resting against the first said flange and its angle resting against the second said flange, and means cooperating with the L-shaped member to increase the pressure of the clamping member upon the pane.

4. In a support for a window pane, a supporting member beyond one edge of the pane and approximately perpendicular to the plane of the pane, a clamping member having a flange along one edge adapted to bear

against the pane, having its other edge adapted to bear against said support and having a flange along the second said edge extending towards the plane of the pane and spaced slightly away from said supporting member, a substantially L-shaped member having the end of one arm resting against the first said flange and its angle resting against the second said flange, and means to force said arm of the L-shaped member against the flange to press the latter against the pane.

5. In a support for a window pane, a supporting member beyond one edge of the pane and approximately perpendicular to the plane of the pane, a clamping member having a flange along one edge adapted to bear against the pane, having its other edge adapted to bear against said support and having a flange along the second said edge extending towards the plane of the pane and spaced slightly away from said supporting member, a substantially L-shaped member having the end of one arm resting against the first said flange and its angle resting against the second said flange, and means to move the angle of the L-shaped member towards the plane of the sheet and towards the support.

6. In a support for a window pane, a supporting member beyond one edge of the pane and approximately perpendicular to the plane of the pane, a clamping member having a flange along one edge adapted to bear against the pane, having its other edge adapted to bear against said support and having a flange along the second said edge extending towards the plane of the pane and spaced slightly away from said supporting member, a substantially L-shaped member having the end of one arm resting against the first said flange and its angle resting against the second said flange, a support for the end of the other arm of the L-shaped member, and means to press on the second said arm in a direction away from said angle and towards said supporting member.

7. In a support for a window pane, a supporting member beyond one edge of the pane and approximately perpendicular to the plane of the same, a clamping member having a flange along one edge adapted to bear against the pane, having its other edge adapted to bear against said support and having a flange along the second said edge extending towards the plane of the pane and spaced slightly away from said supporting member, a substantially L-shaped member having the end of one arm resting against the first said flange and its angle resting against the second said flange, a support for the end of the other arm of the L-shaped member, and means to press on the second said arm in a direction away from said angle and towards said supporting member, said L-

shaped member being constructed with stiffening side flanges to resist bending at its angle.

8. In a support for a window pane, a sup-

- 5 porting member beyond one edge of the pane and approximately perpendicular to the plane of the pane, a clamping member having a flange along one edge adapted to bear against the pane, having its other edge 10 adapted to bear against said support and having a flange along the second said edge extending towards the plane of the pane and spaced slightly away from said supporting member, and a substantially L-shaped member 15 having the end of one arm resting against the first said flange and its angle resting against the second said flange, a support for the end of the other arm of the L-shaped member, and means to press on 20 the second said arm in a direction away from said angle and towards said supporting member, there being a slot in said L-shaped member where it rests on the second said flange, and a portion of the second said 25 flange being bent through the slot.

9. In a support for a window pane, a clamping member having one edge adapted to rest against the pane and having its other edge folded upon itself on the side towards 30 the pane, to form a bead along said edge, and the edge of the folded portion being reversely bent to form a flange extending towards the plane of the pane, means to hold the bead in predetermined position and 35 means to engage and press said flange in a direction away from the first said edge of said member.

10. In a support for a window pane, a clamping member having one edge adapted 40 to rest against the pane and having its other edge folded upon itself on the side towards the pane, to form a bead along said edge, and the edge of the folded portion being reversely bent to form a flange extending to 45 wards the plane of the pane, means to draw said flange towards the plane of the sheet and at the same time to engage and press it in a direction away from the first said edge of said member.

- 50 11. In a support for a window pane, a fixed support, a clamping member having a flange along one edge adapted to rest against a pane, a bead along its other edge adapted to rest against said support and a flange extending from said bead towards the plane of the pane and free from said support, an L-shaped member adapted to have one arm 55 rest against the first said flange and its angle rest against the second said flange, and

means engageable with the other arm of said L-shaped member to force it in a direction to cause the clamping member to bear against the pane.

12. In a support for a window pane, a clamping member having a flange along one edge adapted to rest against the pane, a substantially rigid L-shaped member adapted to have the end of an arm rest against said flange and the other arm extend across the plane of the pane, means connected to 65 the clamping member and engaging the angle of the L-shaped member and yieldable in a direction away from said flange, and means to draw the angle of said L-shaped member towards the plane of the pane.

70 13. In a support for a window pane, a substantially rigid L-shaped member having one arm substantially parallel with the plane of the pane and its other arm extending across the plane of the pane, means to draw the last said arm in a direction away from the angle of the member, and yielding means holding the last said arm from movement in the direction opposite to that in which the first said arm extends from the angle of said 75 member.

14. In a support for a window pane, glass clamping members adapted to be arranged on opposite sides of a sheet of glass, a bracket attached to one of said members, a draw-bar attached to the other of said members and extending across the plane of the glass into proximity to the bracket, a screw passing through the bracket and pressing against the side of the draw-bar, means rigidly supporting the end of the draw-bar against movement away from the bracket, and means yieldingly supporting the middle portion of the draw-bar against movement 80 away from the bracket.

90 15. In a structure of the class described, sheet metal sash members adapted to engage opposite sides of a sheet of glass, a sheet metal bracket of substantially box form engaging one of said members and having an open side towards the other member, a clamping device engaging said other member and having an arm extending into the bracket through its open side and a screw 95 passing through one wall of the bracket and bearing against one side of said arm within the bracket, the bracket at the edge of said opening on the side of the arm opposite said screw being bent at an angle towards said 100 arm to form a yieldable support therefor.

110 In testimony whereof, I have hereunto subscribed my name to this specification.

CHARLES G. NELSON.
